(57) **CLAIM**

The ornamental design of a tape measure, as shown and described.

DESCRIPTION

FIG. 1 is a top-front perspective view of a tape measure showing our new design;

FIG. 2 is a bottom rear perspective view of the tape measure shown in FIG. 1;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The dashed lines shown in the figures represent environmental subject matter and form no part of the claimed design.
